UNITED STATES PATENT OFFICE.

JOSEPH P. KENNEDY, OF CHICAGO, ILLINOIS.

ERASER HOLDER.

Application filed September 28, 1925. Serial No. 59,128.

My invention relates to a holder for black-board erasers and has for its object to provide a device for this purpose which will be strong, durable and cheap to manufacture and which, while taking a firm grip on the black-board structure, preferably on the chalk-rail of the black-board, preventing accidental displacement, will be capable of being readily removed therefrom, if need be, for cleaning the chalk-rail, for example.

A further object is to provide a device so constructed as to be slight in appearance.

The invention is illustrated in the accompanying drawing, in which

Fig. 1 is a view in perspective of the eraser holder shown as applied to the chalk-rail of a black-board of common construction.

Fig. 2 is a sectional view on line 2—2 of Fig. 1.

Fig. 3 is a view similar to Fig. 2 but showing the eraser receiving member as it is about to be attached to the chalk rail, and

Fig. 4 is a view of the retaining member, separately, and as seen from the inner side of said member, that is the side which is toward the black-board when the device is in position on the chalk-rail.

Referring to the drawing, the black-board structure is shown as consisting of a black-board 10 having a strip or bead 11 at its lower edge to which is fastened the chalk-rail 12.

In accordance with my invention the eraser is held on the chalk rail by means of a retaining member 13, composed of sheet metal of some resiliency, preferably, and consisting, in the form of the invention shown in the drawing, of a front plate 14, end projections 15 and a pair of attaching wings 16, 16' which extend back of the front plate, that is between the front plate and the forward edge of the chalk-rail, preferably from the end edges of the front plate. These arrangements might be modified but are deemed particularly suitable for carrying out one of the principles of the invention, namely the provision of an eraser holder attachable to chalk-rails of differing cross-sectional configurations.

The wings 16, 16' are formed with slots 17, preferably tapering, and terminating in circular enlargements 18.

These slotted wings are adapted to engage with attaching elements designed to be permanently fixed to the forward edge

of the chalk rail, the term "permanently" being used in the sense that the fastening devices do not need to be detached when the eraser retaining member is removed for 60 cleaning the chalk from the chalk-rail.

I prefer to use as attaching elements ordinary wood screws 19 having beveled heads 20. Flat headed screws are used in preference to round headed screws in order to obtain a holding pressure, to the maximum extent, as between the retaining member and the black-board structure, resisting accidental displacement of the retaining member while permitting it, nevertheless, to be 70 removed when necessary.

This holding pressure may be developed, through strain of the retaining member, in various ways.

Preferably, the wing 16 is bent toward the front plate 14, that is in the direction from the bend toward the inner end of the wing, while the wing 16' is given a slight bend outwardly. The retaining member is put over the heads of screws 19, with the 80 heads extending through the enlargements 18 of slots 17, and is then moved to the left (Fig. 3). The wings are thus wedged against the bevels of the screw heads resulting in a frictional grip, due to the taper of slots 17, a straightening or flattening out of the wings against the edge of the chalk-rail, produced by the beveling of the screw heads and, preferably, also, the development of a pressure between the front plate and the 90 flat outer surfaces of the screw heads. The strain taking place in the relatively stiff, but slightly resilient retaining member, brings about a bind of the member against the chalk-rail which resists without preventing 95 the detachment of the member from the chalk-rail, which, nevertheless, is readily accomplished by a sharp blow on the left hand end of said member.

It will be understood that this spring grip engagement as between the retaining member and the black-board structure might be accomplished by expedients somewhat different from those just described. For example, it is not essential that the screw 105 heads should project far enough from the chalk-rail to bear against the front plate, although this is desirable in order to increase the holding grip.

It will be observed that the screws are 110 completely covered by the retaining member which adds to the appearance of the device.

and diminishes the likelihood that it will be taken off by some inquisitive child. The strength of the grip is sufficient to deter anyone from attempting to remove the holder from the black-board without knowing just how such removal is to be accomplished.

One important feature of the device is that it can be applied to a chalk-rail of almost any cross-sectional configuration.

10 Other advantages, which will be apparent, are the low cost of manufacture and the ease with which the device may be applied to and removed from the black-board structure. Realizing the possibility of modification within the principles of my invention, I desire to cover the invention in all embodiments within the scope of the appended claims.

I claim:

20 1. A black-board eraser holding device comprising in combination with fastening elements permanently fixed to the black-board structure, a sheet metal retaining member comprising a front plate and in-turned wings adapted to intervene between the front plate and the black board structure which are slotted so as to be engageable with said fastening elements.

25 2. A black-board eraser holding device comprising in combination with fastening elements permanently fixed to the black-board structure, a sheet metal retaining member comprising a front plate and in-turned wings, at opposite ends of said member, adapted to intervene between the front plate and the black board structure which are slotted so as to be engageable with said fastening elements.

30 3. A black-board eraser holding device comprising in combination with fastening elements permanently fixed to the black-board structure, a sheet metal retaining member comprising a front plate and in-turned resilient wings adapted to intervene between the front plate and the black board structure which are slotted for engagement with said fastening element adapted to bear with spring pressure against the black-board structure.

35 4. A black-board eraser holding device comprising in combination with fastening elements permanently fixed to the black-board structure, a sheet metal retaining member having inturned wings slotted for engagement with said fastening elements and bent slightly so as to be adapted to be flattened out against the black-board structure when the retaining member is attached thereto to create a holding pressure.

40 5. A black-board eraser holding device comprising in combination with fastening elements permanently fixed to the black-board structure, a sheet metal retaining member having inturned wings slotted for engagement with said fastening elements and

bent out of parallelism with the body of said member formed so that a pressure is created between the main portion of the retaining member and the outer surfaces of the fastening elements.

6. A black-board eraser holding device comprising in combination with fastening elements permanently fixed to the black-board structure, having undercut beveled heads, an eraser retaining member of spring metal having wings extending between the body of the retaining member and the black-board structure slotted to engage said fastening elements and bent out of parallelism with the body of said member formed so that the retaining member is strained in application to the black-board structure to develop a pressure tending to resist detachment therefrom.

7. A black-board eraser holding device for attachment to the chalk-rail of a black-board comprising in combination with fastening elements permanently fixed to the outer edge of the chalk-rail and having undercut beveled heads, a spring metal eraser retaining member composed of a front plate, end projections extending over the chalk-rail toward the black-board and inturned wings at opposite ends of the front plate slotted to engage said attaching elements.

8. A black-board eraser holding device for attachment to the chalk-rail of a black-board comprising in combination with fastening elements permanently fixed to the outer edge of the chalk-rail and having undercut beveled heads, a metal eraser retaining member composed of a front plate, end projections extending over the chalk-rail toward the black-board and resilient in-turned wings at opposite ends of the front plate slotted to engage said attaching elements and adapted to bear against the chalk-rail with spring pressure.

9. A black-board eraser holding device comprising in combination with attaching means permanently fixed to the black-board structure, a metal eraser-retaining member comprising a plate covering the attaching means and resilient portions strained by application to the black-board structure so that the device is held in place by spring pressure.

10. A black-board eraser holding device for attachment to the chalk-rail of a black-board comprising in combination with beveled flat headed screws fixed to the outer edge of the chalk-rail, a spring-metal eraser retaining member composed of a front plate, end projections extending therefrom toward the black-board and inturned wings at opposite ends of the front plate, one of said wings being convergent with the front plate and the other of said wings divergent from the front plate and both provided with beveled slots terminating in enlargements

whereby the wings may be engaged with said screws.

11. A black-board eraser holding device for attachment to the chalk-rail of a black-board comprising in combination with beveled flat headed screws fixed to the outer edge of the chalk-rail, a spring-metal eraser retaining member composed of a front plate, end projections extending therefrom toward the black-board and inturned wings at opposite ends of the front plate, one of said wings being convergent with the front plate

and the other of said wings divergent from the front plate and both provided with beveled slots terminating in enlargements 15 whereby the wings may be engaged with said screws, said screws projecting from the edge of the chalk-rail far enough so that with the device in place on the chalk rail, the front plate of the retaining member bears 20 with some pressure against the outer surfaces of the screw heads.

JOSEPH P. KENNEDY.
